ALBERT J. ROSENTRETER, OF BOONTON, NEW JERSEY, ASSIGNOR TO EDGAR ZABRISKIE, OF MAPLEWOOD, NEW JERSEY, AND FRANK E. HUTCHINS, OF NEW YORK, N. Y.

DOOR CHECK AND CLOSER.

1,119,878.

Specification of Letters Patent.

Patented Dec. 8, 1914.

Application filed April 10, 1914. Serial No. 830,891.

To all whom it may concern:

Be it known that I, ALBERT J. ROSENTERTER, a citizen of the United States, and resident of Boonton, in the county of Morris 5 and State of New Jersey, have invented certain new and useful Improvements in Door Checks and Closers, of which the following is a specification.

The invention pertains to door checks and 10 closers of the class usually employed on or adjacent to the upper ends of doors for closing the door under the force of a spring controlled by liquid checking means, it being more usual to secure the closing and checking 15 means to the door and connect the same with jointed lever arms secured to the lintel over the door.

The object of the present invention is to 20 produce a greatly simplified and at the same time highly efficient and durable door closer and check adapted for either right or left hand doors, one of the main purposes being to provide a structure which may be readily manufactured at minimum expense and 25 which is devoid of concealed complex features which have given rise to many difficulties when the check has been in use and is required to be repaired or readjusted by carpenters and others unfamiliar with the 30 details of liquid check construction and manipulation.

The more essential features of my invention reside in the supporting and securing bracket to which the liquid checking cylinder 35 is secured and in the cup members constituting the spring chamber and freely mounted on the stud integral with said supporting bracket, together with the details by which said cup members are controlled and also by which one cup member 40 may be rotated to wind the spring from one end during the opening of a right hand door and from the other end during the opening of a left hand door.

45 The invention and its advantages will be fully understood from the detailed description herinafter presented, reference being had to the accompanying drawings, in which:

50 Figure 1 is a top view of a door check and closer constructed in accordance with and embodying the invention and indicated as being applied to or arranged for a right hand door, the several parts being shown in the position 55 they occupy when the door is in its

closed position; Fig. 2 is a horizontal section on a larger scale through the same taken on the dotted line 2-2 of Fig. 4, Fig. 2 showing the supporting bracket in horizontal section and the spring in position in the 60 lower one of the cups of the spring chamber, the upper cup being omitted from Fig. 2 and the central post and spindle therein being shown in top elevation; Fig. 3 is a horizontal section through one end portion of the 65 liquid checking cylinder and devices therein; Fig. 4 is a central vertical section through the door check and closer taken on the dotted line 4-4 of Fig. 5; Fig. 5 is a central vertical section on the dotted line 70 5-5 of Fig. 4 and taken at a right angle to the section of Fig. 4, and Fig. 6 is a sectional view taken on the dotted line 6-6 of Fig. 5, the cylinder being shown as partly broken away.

In the drawings, 10 designates the main supporting bracket for the closer and check, 11 the liquid checking cylinder, and 12 the closing spring, said spring being confined within a spring chamber formed by upper 80 and lower corresponding facing cups 13, 14, respectively, one end of the spring being secured to the upper cup by having the extremity 15 thereof bent upwardly and inserted in a hole in the top of said cup and 85 the other end of the spring being secured to the bottom of the lower cup by the insertion of the downwardly bent extremity 16 thereof in a hole in said cup, as shown in Fig. 4.

The main supporting bracket 10 is in one integral piece and comprises a base plate or member 17 which extends between the upper side of the cylinder 11 and bottom of the lower cup 14, a back 18 of substantially 95 semi-circular outline extending upwardly from the rear edges of the plate 17 and behind the cups 13, 14, and laterally extending ears 19, 19 having holes through which screws may be inserted for securing the 100 bracket against a door or other support. The back 18 extends upwardly to nearly the upper edge of the upper cup 13 and is separated by a semi-circular space from the cups 13, 14, and said back is formed integrally with a vertical stop 20 which is centrally of the back and parallel with the vertical center of the cups 13, 14 with which or with lugs on which said stop co-operates. The base-plate 17 has formed on it a central 110

vertical post or stud 21 which is tubular and receives the spindle 22 for actuating the piston in the cylinder 11. The post 21 is provided at its upper end with a gland for 5 the spindle 22 and lower down is formed with a chamber 23 horizontally encompassing the spindle and from which a port 24 leads downwardly to the interior of the cylinder 11, the chamber 23 and port 24 not being 10 claimed herein and being provided to prevent the oil or other liquid in the cylinder 11 from creeping up to the upper end of the spindle 22. The base plate 17 is formed around the lower end of the post 21 15 with a raised seat 25 for the central portion of the lower cup 14, the main part of the lower surface of the cup 14 being, by means of said seat, elevated slightly from the plate 17 and thus kept from frictional engagement 20 with said plate. At the lower side of the plate 17 and in line with the post 21 is formed a hub 26 through which the spindle 22 passes and which extends downwardly through an opening in the upper side of the 25 cylinder 11.

The upper central portions of the cylinder 11 are formed with front and rear lateral flanges 27, and said cylinder is, at said flanges, secured to the horizontal member 17 30 of the bracket 10 by means of screws 28, these screws being removable whenever it may be desired to dismember the parts of the device. The connection of the cylinder with the supporting bracket 10 by means of 35 the screws 28 renders the assembling of the parts very easy, and in addition the construction of the cylinder separate from the supporting bracket renders the manufacture of the several parts of the device very convenient 40 and satisfactory as well as at a less cost than when the supporting bracket, spring chamber and cylinder of a door check are formed in one piece. The cylinder 11 aside from being separate from the supporting 45 bracket and secured thereto by screws is not of unusual construction, said cylinder being permanently closed at one end and closed at the other end by the plug or cap 29 and containing in one wall a by-pass 30 under 50 the control of an adjusting screw 31. Within the cylinder 11 is located a valved piston 32 of usual construction pivotally connected by a link 33 with a pin 34 carried at the outer end of a crank arm 35 55 which is secured to the lower end of the spindle 22.

The cup members 13, 14 are exposed and each comprises a closed end and an open end, and the open ends of said members are 60 closely adjacent to each other, the exterior wall 36 of the cup 13 extending downwardly and meeting the corresponding wall 37 of the cup 14. The cup members 13, 14 are formed at their interior with sleeves 38, 65 which, like the exterior portions 36, 37 of

said cups, meet each other, so that finally the upper cup 13 rests at its lower outer and inner edges on the corresponding edges of the cup 14 and there is formed between the outer walls of said cups and the inner sleeve 70 members 38 thereof a spring chamber for the spring 12. The cups 13, 14, while engaging each other and mounted on the post or stud 21, are independently rotatable, the upper cup being adapted to rotate on the post 21 and upper edges of the cup 14 while the latter is held stationary, and the cup 14 being adapted to rotate on the post 21 and seat 25 and against the lower edges of the cup 13 while said cup 13 is held stationary. 75 The manner of connecting the ends of the spring 12 with the respective cups 13, 14 has been hereinbefore described. 80

The cups 13, 14 have plain interior and exterior surfaces, except that on their rear sides the cup 13 is formed integrally with a lug 39 which extends downwardly, as shown in Fig. 6, below the joint between the cups 13, 14 and in position to engage the stop 20 cast on the back 18 of the supporting 90 bracket 10, and the cup 14 is formed integrally with a lug 40 which extends upwardly beyond the joint between the cups 13, 14 and is in position to engage the stop 20. The lugs 39, 40 extend both above and 95 below the joint between the cups 13, 14 so that said lugs, one or the other, may always be against the stop 20 and so that said lugs, may, one at a time, be acted on by a depending arm 41 of a right-angular bar or frame 100 42 comprising the said arm 41 which is vertical and a horizontal arm 43 which extends across the top of the upper cup 13 and at its free end is of hub formation, as at 44, and formed at its outer arc-shaped edge with 105 gear teeth 45. The outer or hub portion 44 of the right-angular bar 42 is freely mounted on the upper portion of the spindle 22 and directly over the top of the upper cup 13, and normally, as when a door employing 110 the check is in closed position, the arm 41 of the bar 42 is directly above the stop 20 of the back 18 and between the lugs 39, 40 carried by the cups, as shown in Fig. 6.

Above the hub portion 44 of the bar or 115 frame 42 the spindle 22 has flattened sides, as shown in Fig. 2, upon which a square hole in the inner end of the lever arm 46 is placed, and above said lever arm 46 the spindle 22 is threaded to receive a nut 47 by 120 which the lever arm is held securely upon the upper end of the spindle. The lever arm 46 is a feature of usual construction and it is connected to the link arm 48 of 125 known construction and operation and which at one end is pivotally connected with the outer end of the arm 46 and at its other end is pivotally connected to a bracket 49 by which the link may be secured to the lintel over a door or other required surface. 130

The oscillatory movement of the lever arm 46 serves to rotate the spindle 22 and thereby move the piston 32 in the cylinder 11, the door being checked in its closing movement by the pressure of the piston against the liquid in the cylinder, in a known manner. It is desired that the movement of the lever arm 46 should also serve to wind the spring 12 from one end or the other during the opening of the door so that upon the release of the door the spring may operate to close the door, and to this end I provide the lever arm 46 with a pivoted dog 50 having two engaging points, one or the other of which will be in engagement with a tooth of the series 45 formed on the hub 44 of the bar or frame 42; and it will be obvious that when the dog 50 is in engagement with the teeth 45, the movement of the lever arm 46 will be communicated to the bar or frame 42, and that under such condition the arm 41 of said bar or frame will be carried concentrically with the spindle 22 against one or the other of the lugs 39, 40 and effect the rotation of one or the other of the cups 13, 14 in accordance with its direction of movement. When the dog 50 is in the position in which it is shown in Fig. 1, adapting the check and closer for a right hand door, the arm 41 will, on the opening of the door, be moved against the stop 39 on the upper cup member 13 and cause said member to rotate toward the left, looking at Fig. 1, thereby winding the spring 12 from its upper end, while the lower end of said spring is held stationary by the engagement of the lug 40 on the lower cup 14 with the stop 20. In applying the door check and closer to a left hand door the dog or pawl 50 will be given a reverse position to that shown in Fig. 1 or swung over so that the right hand toe or point thereof, looking at Fig. 1, will engage one of the teeth 45, and then when the door bearing the structure is opened, the arm 41 will engage the lug 40 on the cup 14 and effect the rotation of said cup and the winding of the spring 12 from the lower end thereof, the upper end of the spring then being held stationary by the cup 13 whose lug 39 will be against the stop 20. It will be observed that the operation of the door check and closer is extremely plain and simple and that the device may be readily applied by an unskilled person to a right or a left hand door, as occasion may require. The bar or frame 42 and the lugs 39, 40 with which it coacts, are all exposed, and therefore they may be readily observed, and in addition by their exposure the spring chamber is left unoccupied except by the spring, which is a very great advantage over many door checks and closers in which the interior of the spring chamber is provided with various concealed devices for adapting the structure for right and left hand doors.

The cup members 13, 14 have at their inner tubular portions extended bearing surfaces to engage the stud or post 21, and hence have a smooth uniform movement and are rendered extremely durable. I prefer to make the cup members 13, 14 exactly alike, so that either member may be at the top or either member at the bottom, thus avoiding any mistakes in assembling and avoiding even the requirement of any thought as to which cup member is to be at the top or which at the bottom. I do not desire to limit my invention however to making the cup members 13, 14 of exactly the same proportions, since with less advantage one cup member may be deeper than the other. The cup members 13, 14 are capable of being very readily cast and prepared for use on the post or stud 21. The manner of connecting the spring 12 with the cup members is also devoid of complication or material expense.

I deem the form and construction of the main supporting bracket 10 having the base plate 17 and stud or post 21 as of considerable importance, since when said bracket is constructed as shown and described, it is admirably adapted to receive and permit the proper operation of the cup members 13, 14 and in addition permits the cylinder 11 to be separately constructed and secured thereto by means of screws which may be readily applied or withdrawn. The structure as a whole has been designed with a view of attaining in a device of this class extreme simplicity and durability and the provision of a door check and closer which may be manufactured at reasonable expense. The cup members 13, 14 constitute a sectional inclosing casing for the spring and, in the construction presented, each of said members is rotatable independently of the other; this construction and arrangement admits of the door check and closer being employed for either a right hand door or a left hand door. If it should be desired, however, to construct the door checks and closers separately for right hand doors and for left hand doors, the articles might be manufactured with one or the other of the cup members non-rotatable.

My invention is not confined to details of form and construction otherwise than the following claims may require.

What I claim, is:

1. In a door-closer, a supporting bracket, a spring inclosing casing comprising upper and lower independent members, a coiled spring confined within said casing and having one end connected with the upper member thereof and its other end with the lower member thereof, a vertical stud extending through said members, a spindle mounted in said stud, an operating lever arm connected with said spindle, and exposed means movable with said spindle to exteriorly en-

gage a rotary member of said casing for winding the spring therefrom, said supporting bracket being provided with a stop to hold said rotary member of the casing in its initial position.

2. In a door-closer, a supporting bracket, a spring inclosing casing comprising upper and lower independent rotary members, a spring confined within said casing and having one end connected with the upper member thereof and its other end with the lower member thereof, a vertical stud extending through said members and constituting the axis thereof, a spindle mounted in said stud, an operating lever arm connected with said spindle and exposed means movable with said spindle to exteriorly engage said rotary members for winding the spring therefrom at its respective ends, said supporting bracket being provided with a stop to hold said rotary members in their initial position and allow either to be rotated from said exposed means.

3. In a door-closer, a supporting bracket, a spring inclosing casing comprising upper and lower independent members, a coiled spring confined within said casing and having one end connected with the upper member thereof and its other end with the lower member thereof, a vertical stud extending through said members, a spindle mounted in said stud, an operating lever arm connected with said spindle, and exposed means movable with said spindle to exteriorly engage a rotary member of said casing for winding the spring therefrom, said supporting bracket being provided with a stop to hold said rotary member of the casing in its initial position, combined with a checking cylinder carried by said bracket, a piston therein, and means connecting said spindle and piston for operating the piston from the spindle.

4. In a door-closer, a supporting bracket, a spring inclosing casing comprising upper and lower independent rotary members, a spring confined within said casing and having one end connected with the upper member thereof and its other end with the lower member thereof, a vertical stud extending through said members and constituting the axis thereof, a spindle mounted in said stud, an operating lever arm connected with said spindle and exposed means movable with said spindle to exteriorly engage said rotary members for winding the spring therefrom at its respective ends, said supporting bracket being provided with a stop to hold said rotary members in their initial position and allow either to be rotated from said exposed means, combined with a checking cylinder carried by said bracket, a piston therein, and means connecting said spindle and piston for operating the piston from the spindle.

5. In a door-closer, a supporting bracket, a spring inclosing casing comprising matching upper and lower independent rotary members, a double-acting coiled spring confined within said casing and having one end connected with the upper member thereof and the other end with the lower member thereof, a vertical stud extending through said members and constituting the axis thereof, a spindle mounted in said stud, an operating lever arm connected with said spindle, and a frame exterior to said casing and movable with said spindle to exteriorly engage said rotary members for rotating one or the other thereof for winding the spring therefrom at its respective ends, said supporting bracket being provided with a stop to hold said rotary members in their initial position and allow either to be rotated from said frame, and said rotary members having lugs to engage opposite edges of said stop, and said frame having an arm extending between said lugs to engage one or the other thereof in accordance with its direction of movement.

6. In a door-closer, a supporting bracket, a spring inclosing casing comprising matching upper and lower independent rotary members, a double-acting coiled spring confined within said casing and having one end connected with the upper member thereof and the other end with the lower member thereof, a vertical stud extending through said members and constituting the axis thereof, a spindle mounted in said stud, an operating lever arm connected with said spindle, and a frame exterior to said casing and movable with said spindle to exteriorly engage said rotary members for rotating one or the other thereof for winding the spring therefrom at its respective ends, said supporting bracket being provided with a stop to hold said rotary members in their initial position and allow either to be rotated from said frame, and said rotary members having lugs to engage opposite edges of said stop, and said frame having an arm extending between said lugs to engage one or the other thereof in accordance with its direction of movement, combined with a checking cylinder carried by said bracket, a piston therein, and means connecting said spindle and piston for operating the piston from the spindle.

7. In a door closer, a supporting bracket, a spring inclosing casing comprising upper and lower independent rotary cup-members, a double-acting coiled spring confined within said casing and having one end connected with the upper member thereof and the other end with the lower member thereof, a vertical spindle concentric with said casing, an operating lever arm connected with said spindle, and a right-angular frame exterior to said casing and movable with said spindle

- to exteriorly engage said cup-members for rotating one or the other thereof for winding the spring therefrom at its respective ends, said supporting bracket being provided with a stop to hold said rotary members in their initial position and allow either to be rotated from said frame, said rotary members having lugs to engage opposite edges of said stop, and said frame being extended across the top of said casing and having a depending arm extending between said lugs to engage one or the other thereof in accordance with its direction of movement.
8. In a door closer, a supporting bracket, a spring inclosing casing comprising upper and lower independent rotary cup-members, a double-acting coiled spring confined within said casing and having one end connected with the upper member thereof and the other end with the lower member thereof, a vertical spindle concentric with said casing, an operating lever arm connected with said spindle, and a right-angular frame exterior to said casing and movable with said spindle to exteriorly engage said cup-members for rotating one or the other thereof for winding the spring therefrom at its respective ends, said supporting bracket being provided with a stop to hold said rotary members in their initial position and allow either to be rotated from said frame, said rotary members having lugs to engage opposite edges of said stop, and said frame being extended across the top of said casing and having a depending arm extending between said lugs to engage one or the other thereof in accordance with its direction of movement, combined with a checking cylinder carried by said bracket, a piston therein, and means connecting said spindle and piston for operating the piston from the spindle.
9. In a door closer, a supporting bracket, a spring inclosing casing comprising upper and lower independent rotary cup-members, a double-acting coiled spring confined within said casing and having one end connected with the upper member thereof and the other end with the lower member thereof, a vertical spindle concentric with said casing, an operating lever arm connected with said spindle, and a right-angular frame exterior to said casing and movable with and mounted on said spindle to exteriorly engage said cup-members for rotating one or the other thereof for winding the spring therefrom at its respective ends, said supporting bracket being provided with a stop to hold said rotary members in their initial position and allow either to be rotated from said frame, said rotary members having lugs to engage opposite edges of said stop, said frame being extended across the top of said casing and having a depending arm extending between
- said lugs to engage one or the other thereof in accordance with its direction of movement, and said frame having adjacent to said spindle a toothed edge, and said lever arm having a pivoted pawl with two teeth either of which may engage a tooth of said edge.
10. In a door-closer, a supporting bracket, a spring inclosing casing comprising upper and lower independent rotary matching cup-members, a double-acting coiled spring confined within said casing and having one end connected with the upper member thereof and the other end with the lower member thereof, a vertical spindle concentric with said casing, an operating lever arm connected with said spindle, exposed means movable with said spindle to exteriorly engage said rotary members for winding the spring therefrom at its respective ends, and means for holding said rotary members in their initial position and allowing either to be rotated from said exposed means.
11. In a door-closer, a supporting bracket, a spring inclosing casing comprising upper and lower independent rotary matching cup-members having tubular bearing sleeves at their vertical center, a double-acting coiled spring confined within said casing and having one end connected with the upper member thereof and the other end with the lower member thereof, a rigid stud on which said cup members are mounted, a vertical spindle mounted in said stud, an operating lever arm carrying a double-acting pawl and connected with said spindle, exposed means engaged by said pawl and movable with said spindle to exteriorly engage said rotary members for winding the spring therefrom at its respective ends, and means for holding said rotary members in their initial position and allowing either to be rotated from said exposed means.
12. In a door-closer, a supporting bracket comprising a back, a horizontal plate and an integral stud extending vertically at right angles to said plate, a spring inclosing casing comprising upper and lower independent rotary members mounted on said stud, a double acting coiled spring confined within said casing and having one end connected with the upper member thereof and the other end with the lower member thereof, a vertical spindle mounted in said stud, an operating lever arm connected with said spindle and carrying a pivoted dog or pawl, exposed means movable with said spindle and mounted thereon to engage said rotary members for winding the spring therefrom at its respective ends, and means for holding said rotary members in their initial position and allowing either to be rotated from said exposed means, said exposed means having a toothed edge to be engaged by said dog or pawl.

13. In a door-closer, a supporting bracket comprising a back, a horizontal plate and an integral stud extending vertically at right angles to said plate, a spring inclosing casing comprising upper and lower independent rotary members mounted on said stud, a double acting coiled spring confined within said casing and having one end connected with the upper member thereof and the other end with the lower member thereof, a vertical spindle mounted in said stud, an operating lever arm connected with said spindle and carrying a pivoted dog or pawl, exposed means movable with said spindle and mounted thereon to engage said rotary members for winding the spring therefrom at its respective ends, and means for holding said rotary members in their initial position and allowing either to be rotated from said exposed means, said exposed means having a toothed edge to be engaged by said dog or pawl, combined with a checking cylinder at the lower side of said plate, a piston therein, and means connecting said spindle and piston for operating the piston from the spindle.
- Signed at New York city, in the county of New York and State of New York, this 9th day of April, A. D. 1914.
- ALBERT J. ROSENTRETER.
